US0D1057118S

(12) **United States Design Patent** (10) **Patent No.:** **US D1,057,118 S**
(45) **Date of Patent:** **** Jan. 7, 2025**

(54) **HOUSING FOR A HEAT EXCHANGER**

(71) Applicant: **Dometic Sweden AB**, Solna (SE)

(72) Inventors: **Anna-Carin M. Neale**, Farsta (SE);
Anoop Muthu, Kerala (IN); **Pär Gustafsson Maniette**, Huddinge (SE)

(73) Assignee: **Dometic Sweden AB**, Solna (SE)

(**) Term: **15 Years**

(21) Appl. No.: **29/826,755**

(22) Filed: **Feb. 15, 2022**

(30) **Foreign Application Priority Data**
